ENVELOPE SEALER

Thomas John Jones, Winnipeg, Manitoba,
Canada

Application May 9, 1934, Serial No. 724,796

7 Claims. (Cl. 120—6)

The invention relates to improvements in envelope sealers and an object of the invention is, to provide a device for moistening the gummed flap of an envelope and subsequently sealing the 5 same in one operation.

A further object of the invention is, to provide a moistening pad, carried by the sealer and construct the sealer to permit the pad to revolve and also design the sealer such, that the gummed 10 flap of the envelope will be positively pressed against the pad in the initial part of the sealing operation.

A further object of the invention is, to provide a water reservoir associated with the pad to 15 maintain the said pad in a moistened condition.

A further object of the invention is, to provide a control for the flow of water from the reservoir to the pad.

A still further object of the invention is, to 20 provide air ducts in the upper part of the reservoir to permit the escape of the water through the control without reducing the air pressure within the reservoir.

A still further object of the invention is, to 25 design the device in a simple, cheap and durable manner, the parts being arranged with ample clearance space therebetween for cleaning purposes and to keep the device in a sanitary condition.

With the above important objects in view 30 which will become more apparent as the description proceeds, the invention consists essentially in the arrangement and construction of parts hereinafter, more particularly described, reference being had to the accompanying drawing in which:

Fig. 1 is a perspective view of the envelope sealer in the act of sealing an envelope, and showing the position of the operator's hand in dotted 35 outline.

Fig. 2 is a plan view of the envelope sealer with the reservoir removed but shown in dotted outline.

Fig. 3 is a vertical, sectional view taken at 3—3

Fig. 2.

Fig. 4 is a vertical, sectional view taken at 4—4

Fig. 2.

Fig. 5 is a vertical, sectional view taken at 5—5

Fig. 2.

Fig. 6 is a vertical, sectional view taken at 6—6

Fig. 2.

In the drawing like characters of reference indicate corresponding parts in the several figures.

A rectangular shaped bar 1 comprises the 55 frame of the envelope sealer and a partially, cir-

cular, supporting plate or shelf 2 extends to the side thereof from the forward end. This plate, starting from the lower part of the bar 1 is designed to slope upward at a slight angle and the edges thereof are rounded or beveled for a purpose later described. From the rear of the bar 1 and to the side thereof, a pressure or sealing bar 3 extends of solid, circular cross section. This bar is directly behind the plate 2 and its lower extremity is slightly lower than the bottom of the bar 1. From the drawing it will be observed, that the bar 1, the plate 2 and the sealing bar 3 are all cast in one piece.

The upper face of the plate 2 is provided with a circular depression 4 to receive a circular 15 shaped moisture pad 5. This pad is of suitable absorbent material and is centered in the depression by a stud 6 which extends upward from the plate and passes through the pad permitting it to be rotated.

A semi-circular opening 7 is cut in the upper, front end of the bar 1 and this opening receives a circular tank or reservoir 8 which terminates flush with one side of the bar and the other end extends over the moisture pad 5 and terminates 25 slightly past the plate 2. Both ends of the reservoir are closed by plates 9 and 10 and a fastening screw 11 passes up through the bar 1, through the reservoir casing and into the plate 10 securing the reservoir to the bar.

In the bottom of the reservoir and adjacent the inner side of the pad, an outlet hole 12 is located and this is normally closed by a needle valve 13, suitably controlled by a thumb nut 14 from the top of the reservoir. A filler cap 15 is 30 screw threaded into the top of the reservoir adjacent the thumb nut and an air duct 16 is provided 35 therein. A further air duct 17 is provided in the upper part of the closure plate 10.

From the above, and assuming that the reservoir is supplied with a quantity of water, the thumb nut can be turned and water will flow 40 through the opening 12 onto the pad 5, while air replaces the water through the ducts 16 and 17 in the reservoir.

In operation, when a large number of envelopes are to be sealed, the thumb nut is set 45 at a predetermined position which will be found in practice and water then drips on the pad. The operator places his thumb on the end of 50 the bar 1, the index finger on the pressure bar 3 and the other fingers on the side of the reservoir (see Fig. 1), with the left hand holding the envelope. The rounded or beveled edge of the plate 2 is slipped under the end of the envelope 55

flap while the pressure bar is adapted to pass over the flap in the movement of the sealer. As the plate 2 is elevated considerably above the bottom of the pressure bar the flap takes the form of an ogee curve as indicated at 18 Fig. 1 causing the gummed under side to positively contact with the moistened pad. The sealer is then moved along the flap and the friction between the gum and the pad causes the pad to revolve bringing the part of the pad receiving the water from the reservoir directly into contact with the gum and, the pressure bar, passing over the flap effectively seals the same.

If only a few envelopes are to be sealed the thumb nut is just turned on for a few moments until the pad is wet and then tightened again. This will usually be sufficient for the purpose.

While it is recognized that there are a number of envelope sealers on the market, it is found that they invariably, have a closed passage for the flaps of the envelopes to travel through. Dust and dirt collect in this passage, when not in use and it is extremely hard to keep it in a clean and sanitary condition. Further, the reservoirs are not provided with air ducts to prevent the reduction in the air pressure when the water passes out with the result that the water is locked therein and the device is useless unless the filler cap is removed, and then, water is liable to splash on the envelope.

With this device, all parts are readily accessible for cleaning purposes and the air ducts insure that a continuous supply of water will be assured. The pressure bar being lower than the plate 2, positively forces the flap against the body of the envelope with the result that, provided the gum is moist, an unsealed envelope is a rare exception.

What I claim as my invention is:

1. In an envelope sealer, a flat, circular, moisture pad, horizontally mounted on a pin for free rotation and adapted to turn when the upper face thereof is brought into frictional contact with the gummed surface of an envelope flap.
2. In an envelope sealer construction, a flat, circular, moisture pad mounted for free rotation in a horizontal plane, a reservoir having means

for conducting liquid to the upper side of the pad and the said pad adapted to turn under frictional contact with the gummed flap of an envelope to bring the previously moistened portion into position for contact with subsequent flaps.

3. In an envelope sealer, a flat, circular, moisture pad horizontally mounted on a sloping shelf for free rotation and adapted to turn when the upper face thereof is brought into frictional contact with the gummed surface of an envelope flap.

4. An envelope sealer comprising a moisture pad mounted on a pin for horizontal rotation and supported on a sloping shelf, a reservoir overlying the pad, slightly to the rear thereof and spaced therefrom, an outlet in the bottom of the reservoir communicating with the lower side of the pad, an air duct in the upper portion of the reservoir and a cylindrical sealing bar mounted rearwardly of the pad, spaced therefrom and having its lower extremity below the pad, the shelf, reservoir and sealing bar connected by a connecting bar.

5. An envelope sealer, comprising a moisture pad supported on a shelf, a cylinder directly overlying the pad, a cylindrical shaped sealing bar located behind the shelf and having its lower extremity below the pad, the said shelf, cylinder and sealing bar being spaced apart and connected to a side base bar.

6. An envelope sealer comprising a moisture pad supported on a sloping shelf, a cylinder directly overlying the pad, a cylindrical shaped sealing bar located behind the shelf, parallel with the cylinder and having its lower extremity below the pad, the said shelf, cylinder and sealing bar being spaced apart and connected to a side base bar.

7. In an envelope sealer, a moisture pad mounted on a permanent sloping shelf, means for delivering liquid to the lowest point of the pad for contact with the gummed surface of passing envelope flaps and the sloping angle of the pad adapted to drain surplus liquid from the point of flap contact.

THOMAS JOHN JONES.
